GARMENT COUNTER

Application filed March 8, 1928. Serial No. 260,026.

This invention relates to a counting device, and particularly to an improved garment counting device, the object being to provide a construction which will receive garments and hold the same in a given position, the structure functioning to count the garments as they are placed in the device.

Another object of the invention is to provide a garment counter for stockings or other garments, wherein counting mechanism is automatically operated as the garments are placed in a holder which is automatically closed when a predetermined number of garments has been placed therein, thus insuring an accurate count at all times.

A still further object of the invention is to provide a garment counting device which will function to count garments when placed in the device, and which will function to reset the counting mechanism when the garments are removed from the device.

In the accompanying drawing—

Figure 1 is a front view of a garment counter, disclosing an embodiment of the invention, certain parts being broken away for illustrating part of the counting mechanism.

Figure 2 is an edge view of the counter shown in Figure 1, certain parts being broken away for illustrating in side elevation certain of the counting mechanism.

Figure 3 is an elevation of the upper part of the structure shown in Figure 1 with the front plate and associated parts removed.

Figure 4 is a fragmentary view of certain of the parts shown in Figure 3, but with said parts in a different position.

Figure 5 is a view similar to Figure 4, but with the parts in a different position indicating the action when the counting mechanism is released.

Figure 6 is a detail fragmentary sectional view through Figure 2 on line 6—6.

Referring to the accompanying drawing by numerals, 1 indicates a shank which is shown as bifurcated at 2. A suitable clamping screw 3 is provided whereby the bifurcated portion 2 may be clamped to a support of any kind. Shank 1 merges into a fork structure formed by tines 4 and 5. These tines are preferably parallel for part of the

distance and then flared at the upper end. The flared end 6 of tine 5 is formed with a pair of spaced flanges 7 having a runway 8 therebetween. The runway or groove 8 accommodates the free end of the counting lever 9 which must pass through the groove and to a position near the tine 4, as each garment is placed between the tines and is caused to rest on the supporting surface 10 or upon garments already placed on this surface. After each garment has been placed in position, a counting lever 9 automatically resumes the position shown in full lines in Figure 9 so that it must be depressed a second time for a second garment and so on for as many garments as the device will hold, or for as many times as the device is set to receive.

Lever 9 is connected with suitable counting mechanism carried by the tine 4, and this counting mechanism is caused to function upon each downward movement of the lever 9, said functioning not taking place until after the free end of lever 9 has passed out of the groove 8, thus allowing a little free movement. After the desired number of garments has been inserted, the lever 9 as hereinafter fully described, is locked against being depressed but may be unlocked by moving the same upwardly to the upper dotted position shown in Figure 2. This upward movement is usually caused by bodily removing all of the garments between the tines 4 and 5.

As soon as the garments have been moved out from between the tines or holding structure, lever 9 will automatically resume the position shown in Figure 2. Preferably the tine 4 is provided with an integral upstanding flange structure 11 which is adapted to be covered by plate 12, whereby a chamber 13 is presented. Plate 12 is provided with a window 14 through which the various numbers 15 on the dial 16 may be seen as they move past. The plate 12 is also provided with an arc-shaped slot 17 through which the spring arm 18 of the ball 19 extends. The ball 19 acts as a striker for striking the bell 20 to produce a sound upon the insertion of each garment. Bell 20 is also sounded when all of the garments are removed. A shaft 21

is screwed into or otherwise rigidly secured to the tine 4 and extends outwardly therefrom through certain parts including the dial plate 16 and the cover 12. This shaft is 5 threaded so that the nut 22 will act to clamp the plate 12 in position, and also act to hold the other parts in position. The bell 20 is secured in any desired manner to the outer end of the shaft so that as the device is operated, ball 19 may strike the bell from time to time. A ratchet wheel 23 is rotatably mounted on the shaft 21 near the point it is secured to the tine 4. Preferably integral with the ratchet wheel 23 is a disk 24 provided 10 with a notch or aperture 25 and a notch 26. The aperture 25 is really a hole which extends through the disk 24 but not necessarily through the ratchet wheel 23, though if it should be formed so as to extend through 15 the ratchet wheel 23 there would be no objection. There is one tooth on ratchet wheel 23 for each of the numbers 15, and in a specific device there may be twenty-four numbers 15 so that twenty-four articles may be counted 20 by the device. If a less number of articles are to be counted, ratchet wheel 23 and disk 24 are removed and a new ratchet wheel and disk provided, the new ratchet wheel having a different number of teeth, though the new 25 disk 24 will be provided with the aperture 25 and the notch 26 in the same manner. A spring actuated pawl 27 is provided for preventing a reverse movement of the ratchet wheel 23, while a reciprocating pawl 28 is 30 provided with a tooth 29 adapted to engage the teeth of wheel 23 for intermittently moving wheel 23. The pawl 28 is pivotally mounted on lever 9 at point 30 and lever 9 in turn is pivotally mounted on the tine 4 at 31. In 35 this way, whenever the lever 9 is swung in either direction, pawl 28 will be correspondingly moved.

A retractile spring 32 is connected to the arm 33 of pawl 28, and is also connected at 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

and the ratchet wheel 23 provided with twenty-five teeth, one tooth being non-effective by reason of the movement of the lag 16 out of notch 26, said movement taking place when the lever 9 is moved to the upper dotted position shown in Figure 2 and then released. A comparatively long retractile spring 41 is connected at 42 to the enlargement 38 and at 34 to the lever 35 so as to tend to hold the lever against the periphery of the disk 24 and to cause the lever to move for forcing lug 36 into notch 26 whenever possible. In this way, a person counting stockings or other garments, may pass the garments individually or in pairs, into the forked holder formed by the tines 4 and 5, and the articles will be automatically counted. Not only will the articles be automatically counted, but the holder will be closed against the insertion of more than the correct number as 85 lever 9 will be locked against downward movement as soon as the lug 36 enters notch 26.

Another advantage in the construction and arrangement of the parts described, is that 90 as soon as the counted articles have been removed, the parts are automatically reset so that a workman need only to place articles in the holder and remove the same and the counting operation will automatically follow without any adjustment or resetting by the operator. As the lever 9 functions during the counting operation, it will raise the pawl 28 longitudinally upwardly against the action of spring 32. When the lever 9 is moved upwardly to the upper dotted position shown in Figure 2, pawl 28 will be moved downwardly an extra long distance against the action of spring 41. During the downward movement under these circumstances, the 100 lower end of the pawl will strike the lever 35 and depress the same as shown in Figure 5. Preferably the lower end of pawl 38 is provided with an enlargement 43 extending substantially at right angles to the general direction of the pawl, whereby lever 35 will always be engaged and swung as shown in Figure 5 when the pawl is moved downwardly as just described. When this action takes place, the tooth 29 engages one of the teeth 110 of the ratchet wheel 23, and as the pawl moves upwardly, it will rotate the ratchet wheel 23 and disk 24 the distance of one tooth before lever 35 can resume its former position and, consequently, as lever 35 swings backward toward its former position, lug 36 will strike the periphery of disk 24 at one side of notch 26. This will produce an unlocked condition and permit the counting lever 9 to function as 115 described.

What we claim is:

1. A garment counter, comprising a forked holder adapted to receive garments and support the same, a lever pivotally mounted on one of the forks of said holder, said lever ex- 130

tending across to the opposite fork whereby each garment forced into the fork will actuate said lever in one direction, counting mechanism operatively connected with said lever and caused to function each time said lever is actuated by the movement of an article into said forked support, means for locking said counting mechanism in said lever against functioning after said lever has been actuated 5 a certain number of times, and means operated by a movement of said lever in the opposite direction for unlocking said counting mechanism.

2. A counter for stockings and other garments, comprising a holder provided with an entrance opening, a counting lever pivotally mounted in said holder and extending across said entrance opening whereby the articles as they are forced through said entrance 10 opening will swing said lever in one direction, means forming a guiding path for the free end of said counting lever, a counting mechanism operatively connected with the opposite end of said lever, said counting mechanism functioning each time said lever is swung on its pivotal support, means for automatically locking said counting mechanism after the same has functioned to a predetermined extent, and means actuated by 15 said counting lever for unlocking said locking means.

3. A garment counter, comprising a forked structure adapted to receive garments, a counting lever pivotally mounted so as to extend across the open end of said forked structure whereby garments placed in the forked structure will swing the counting lever, means forming counting mechanism, said means being operated by said counting member, a locking lever for locking said counting mechanism after it has moved a certain number of times, and means for moving said locking lever out of functioning position, said means being connected with said counting lever and 20 caused to function when said counting lever has been moved in a reverse direction.

4. A garment counter, comprising a holder for receiving garments, a lever pivotally mounted and positioned to extend across the 25 opening in said holder whereby the lever is moved upon the insertion of each garment, a pawl moved in one direction by said lever, spring means for moving the pawl and lever back to their first position, a ratchet wheel moved by said pawl, a locking structure for locking said ratchet wheel against functioning after the same has been moved a certain distance, and a projection carried by said pawl adapted to engage said locking structure 30 for moving the same to an inoperative position, when said pawl and said counting lever have been moved a predetermined distance in a reverse direction.

5. In a garment counter, a counting lever, 35 a pawl moved by the counting lever in one

direction, a spring for moving the pawl and counting lever in the opposite direction, a ratchet wheel adapted to be moved a certain distance upon each actuation of the pawl, and a locking lever for locking said ratchet 70 wheel against movement after it has been moved a certain distance, said locking lever being positioned in the path of movement of said pawl whereby when said pawl is moved in one direction a certain distance 75 said locking lever will be shifted to an inoperative position for permitting a further movement of said ratchet wheel.

6. In a garment counter, a counting lever, a pawl adapted to be moved in one direction 80 by said lever when the lever is functioning to count, said pawl being capable of being moved in the opposite direction by said lever, a counting mechanism including a ratchet wheel positioned to be moved a predetermined 85 distance upon each movement of the pawl in one direction, a notched member connected with said ratchet wheel, and a spring held locking lever formed with a lug adapted to move into said notched member when the 90 ratchet wheel has been moved a predetermined distance, said pawl being adapted to engage and swing said locking lever to an inoperative position when said counting lever has been moved in a reverse direction to the 95 direction it moves for counting.

7. In a garment counter, a counting lever adapted to be swung in one direction for counting and capable of being swung in an opposite direction, a pawl pivotally connected 100 to one end of said lever, a counting mechanism actuated by said pawl, said counting mechanism being formed with means having a notch, a spring held lever having a lug positioned to move into said notch when the 105 counting mechanism has been moved by said pawl to a certain position, said locking lever being capable of being moved to an inoperative position when said counting lever has been moved a predetermined distance in a 110 reverse direction to that moved when counting.

8. A garment counter, comprising a holder, a counting lever pivotally mounted on said holder, a ratchet wheel carried by the holder, 115 a pawl pivotally connected with said counting lever and positioned to engage said ratchet wheel for moving the ratchet wheel as the counting lever is moved, a disk rigidly secured to said ratchet wheel, said disk having a notch 120 therein, a locking lever formed with a lug positioned to slidingly engage the periphery of said disk, a spring acting on said lever so that when said disk is moved for one revolution said lug will move into said notch and lock the disk and the wheel and associated parts against further operation, said pawl having an extension projecting to a point 125 near said locking lever whereby when said counting lever is moved in one direction, said 130

pawl will engage said locking lever and swing the same away from said disk while engaging one of the teeth of said ratchet wheel, and spring means for restoring said pawl and associated parts to their former position, said spring means causing said pawl to engage said ratchet wheel and move the same the distance of one tooth before said locking lever can move back into engagement with said disk whereby the disk, ratchet wheel and associated parts are unlocked and the device is in position for again functioning.
